SCRAPER MECHANISM

Filed Oct. 4, 1927

INVENTOR
ANDREW J. CLAUSEN
BY Charles J. Ermak
HIS ATTORNEY.

UNITED STATES PATENT OFFICE

ANDREW J. CLAUSEN, OF SAN FRANCISCO, CALIFORNIA

SCRAPER MECHANISM

Application filed October 4, 1927. Serial No. 223,868.

My invention relates to scraper mechanisms adapted to be used with machines for finishing concrete roads, and particularly with machines using reciprocating strike offs or screeds for working the concrete into place between forming tracks.

An object of my invention is to provide means to prevent waste of concrete over the tracks of a road finishing machine.

Another object is to prevent accumulation of material on the tracks, thus disturbing the alignment of the machine and the level of the finished roadway.

A further object is to provide means whereby undue stresses caused by large objects undesignedly introduced into the aggregate and which might damage the mechanism, are automatically relieved.

My invention has other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

Referring to the drawings:

Figure 1 is a front elevation of a road finishing machine embodying my invention, a portion of the screed being cut away to show the reciprocating mechanism.

Figure 2 is a detail of the scraper, drawn to an enlarged scale.

Broadly considered, my invention comprises a scraper movably attached to the screed adjacent the track. The movement of the scraper renders it effective to move the road forming material away from the track, but ineffective to move the material in the opposite direction. Means are provided for limiting the forces which can be applied to the scraper, to prevent damage due to unduly large or immovable objects accidentally introduced in the path of its movement.

A preferred form of my invention may be applied to a road finishing machine of well known type, comprising the tracks 6, which constitute a form between which the aggregate 7 is worked to form the roadway. On

these tracks run the trucks (not shown) which carry the road finishing machine. This machine comprises the motor 8, which, through the gear trains 9, 11, 12, 13, 14, 16, supplies the power to move the machine along the tracks, to raise the screed 17 or to lower it into operating position as shown, and to impart to the screed, by means of the crank and link mechanism 18, 19, 21, 22, a reciprocating motion transverse to the trackway. Control levers 23 and clutches 24 allow the operator to employ these movements separately or together as the nature of the work may require.

The screed rests on the tracks 6. The portions engaging the tracks are arched or inclined upward slightly toward the center of the machine, and therefore as the screed is reciprocated it describes a slightly arcuate path. The road material or aggregate is dumped in front of the advancing machine, and the screed scrapes and works the aggregate into a solidly compacted roadway, crowned in the center by reason of the arcuate motion of the screed.

The principal difficulty in operating the known device thus briefly described is its tendency to work the aggregate over the tracks, thus wasting material and even blocking the operation of the machine until the track is cleared by the crew. To prevent these wastes is the function of my invention.

Firmly bolted to the screed adjacent the track are the brackets 27, 28, which carry the plate 29. Attached to the plate by the hinge 31 is the scraper 32, which hangs in an approximately vertical position with its lower or scraping edge level with the screed where it rests on the track.

An arm 33, substantially perpendicular to the scraper and riveted thereto, projects under the plate 29. Holes thru plate and arm allow free passage for the bolt 34. Between the head of the bolt and the arm is a washer 36 on which the arm 33 rests, and above the plate a heavy compression spring 37 surrounds the bolt and is surmounted by a washer 38 and a pair of jam nuts 39. Arm, bolt and spring serve as a resilient stop which tends to prevent the scraper from swinging outwardly, but permits it to do so in case it

encounters any object so unwieldly as to damage the equipment.

The inward swing of the scraper is unobstructed. For this reason as it is moved toward the side of the roadway it is ineffective, since it may swing and drag over the aggregate without moving it. When, however, the screed starts to move the scraper toward the center of the roadway it assumes its effective vertical position, scraping the material off of the track and into place in front of the advancing screed.

I claim:

1. In combination with a road finishing machine having a screed, a scraper, means for imparting reciprocating motion thereto longitudinally of the screed, and means for maintaining the scraper in effective position during one stroke of the reciprocating motion and permitting its movement from said position during the recovery stroke.

2. In combination with a road finishing machine having a screed, a scraper, means for imparting reciprocating motion thereto longitudinally of the screed, and resilient means for maintaining the scraper in effective position during one stroke of the reciprocating motion.

3. In combination with a road finishing machine having a screed, a hinged scraper, means for imparting reciprocating motion thereto longitudinally of the screed, and means for maintaining the scraper in effective position during one stroke of the reciprocating motion and permitting it to swing from said position during the recovery stroke.

4. In combination with a road finishing machine having a screed, a scraper, means for imparting reciprocating motion thereto longitudinally of the screed, resilient means for maintaining the scraper in effective position during one stroke of the reciprocating motion and means permitting its movement from said position during its recovery stroke.

45 5. In combination with a road finishing machine working on a track, a scraper mounted on the machine adjacent the track, means for imparting reciprocating motion to the scraper, and means for maintaining the scraper in effective position when moved inwardly from the track and permitting its departure from said position when moved outwardly.

55 6. In combination with a road finishing machine working on a track, a scraper mounted on the machine adjacent the track, means for imparting reciprocating motion to the scraper, resilient means for maintaining the scraper in effective position when moved inwardly from the track and means permitting free movement from said position when moved outwardly.

65 7. In a road finishing machine working on a trackway and employing a reciprocating screed, a plate attached to the screed in a

plane parallel to one of the tracks, a scraper adjacent said track hinged to the plate to permit it to swing freely, and a spring controlled stop limiting its swing outward toward the track except when overstressed.

8. In a road finishing machine, a scraper plate mounted for reciprocating movement across a field of operation, means for permitting the plate to be thrust clear of material in its path of movement when moving in one direction and for fixing the plate to move the material when it is moving in the other direction, and means for resiliently resisting movement of the plate relative to its mounting when moved in said other direction.

9. In a road finishing machine, a scraper plate mounted for reciprocating movement across a field of operation, means for permitting free movement of the plate when stressed in one direction and means for resiliently resisting free movement when stressed in the opposite direction.

10. In combination with a road finishing machine having a reciprocating screed, scrapers hinged to the screed adjacent each end thereof and having their scraping surfaces disposed perpendicular to the scraping edge of the screed, and stops for limiting the outward movement of the scrapers while permitting inward movement thereof.

In testimony whereof, I have hereunto set my hand.

ANDREW J. CLAUSEN.
